UNITED STATES PATENT OFFICE

109,802

DESIGN FOR A COVER FOR A COMPACT BOX

George Gamble, Cambridge, Mass.

Application September 15, 1937, Serial No. 71,637

Term of patent 3½ years

To all whom it may concern:

Be it known that I, George Gamble, a citizen of the United States, residing at Cambridge, county of Middlesex, State of Massachusetts, have invented a new, original, and ornamental Design for a Cover for a Compact Box, of which the following is a specification, reference being had to the accompanying drawing forming part thereof.

In the drawing;

Fig. 1 is a top plan view of a cover for a compact box embodying my design;

Fig. 2 is a side view;

I claim:

The ornamental design for a cover for a compact box as shown.

GEORGE GAMBLE.
